UNITED STATES PATENT OFFICE

DOMENIC CALO, OF ST. ALBANS, VERMONT

ATTACHMENT FOR SHOES

Application filed August 18, 1927. Serial No. 213,757.

My invention relates to new and useful improvements in an attachment for shoes and has for its principal object the provision of a device adapted to be attached to the shoe 5 in such a manner as to protect the upper during repairing of the shoe, the attachment being primarily intended for use in connection with a repairing process wherein a sole is connected to the upper by cement or the like, the sole being pressed into tight engagement with the upper by a suitable machine or tool adapted for the purpose.

Another object of the invention consists in the provision of a device of the character described which may be readily shaped around the edge of the shoe and held in the desired position during the repairing operation and then removed.

With the above and other objects in view, 20 which will appear as the description proceeds, my invention consists in the novel details of construction, and arrangement of parts, described in the following specification and illustrated in the accompanying 25 drawings, and while I have illustrated and described the preferred embodiments of the invention, as they now appear to me, it will be understood that such changes may be made as will fall within the scope of the appended 30 claims.

In the drawings:

Fig. 1 is a side elevation showing my attachment in position upon a shoe.

Fig. 2 is a bottom plan showing the attachment in position.

Fig. 3 is a plan showing the blank from which the attachment is formed; and

Fig. 4 is a section on the line 4—4 of Fig. 1.

In the repairing of shoes there is one process in use wherein the sole is connected to the upper by cement or similar material and the sole is pressed into tight engagement with the upper by means of a suitable machine or tool. It has been found by experience that 40 the cement or other material will be pressed from between the sole and upper, around the edges thereof, and will engage the upper above the sole to disfigure the same. My attachment is adapted to prevent this disfiguring of the upper.

In the drawings 1 indicates the upper of the shoe, 2 the heel, 3 the inner sole, 4 the inner lining, and 5 the outer sole adapted to be secured to the inner sole 3 and upper by cement or the like. As shown more particularly in Fig. 4 of the drawings the lower edge of the upper is folded under the edge of the inner sole 3 and is secured thereto by means of the stitching 6. While primarily intended for repairing shoes it will be understood that my attachment might be used when the shoe is first manufactured and while in the drawings the sole 5 is illustrated as a repair sole it will be understood that it might equally as well be the original sole.

My improved form of attachment is made of tin or other similar readily flexible material and is of the shape more particularly illustrated in Fig. 3 of the drawings consisting of the relatively narrow central portion 7 having the somewhat wider end portions 8 with the projections 9 extending laterally from one edge at the ends. Formed on the edge of the strip between the projections 9 are the teeth 10 and formed in the strip adjacent each end thereof is an opening 11 for a purpose to be later described. Perforations 12 are formed in the strip, intermediate the perforations 11, for a purpose to be later described.

From the above it is thought that the detailed construction of my attachment will be clearly understood. As stated the attachment is of tin or similar flexible material and when the same is to be used it is shaped around the edge of the upper as shown more particularly in Fig. 1 of the drawings and the edge having the teeth 10 is bent to engage under the edge of the upper as shown more particularly in Fig. 4 of the drawings. When the sole 5 is placed in position it will engage beneath the inturned edge of the attachment and aid in holding the attachment in position. When pressure is applied to attach the sole to the upper any surplus of the cement which may be squeezed from between the sole and upper will be prevented from contacting with the upper to disfigure the same. The surplus of cement or the like will be squeezed

towards the edge of the sole and to the outer face of the attachment. The end portions having the projections 9 are bent under the shank of the shoe as shown more particularly in Fig. 2 of the drawings and secured in position by means of the nails 13 or similar attaching devices, which pass through the perforations 11. If desired tacks or similar attaching members may be passed through the perforations 12 for securing the attachment to the upper, although these perforations may not be always necessary.

After the cement has sufficiently set so that there is no danger of any engaging with the upper of the shoe then the attachment is removed. It will be seen that the attachment may be readily shaped around the shoe and for this reason may be used with shoes of different shapes or sizes. The widened end portions of the strip cover a greater surface of the upper adjacent the shank of the shoe giving a greater amount of protection to the upper at these points.

Having fully described my invention what I claim as new and desire to secure by Letters Patent is:

1. A device of the character described adapted to be used in the repairing of shoes consisting of a strip of material having a relatively narrow central portion and widened end portions, the strip being adapted to be shaped around the shoe upper, teeth formed on one edge of the strip, said toothed edge being bent to provide a flange to be engaged between the upper and sole, and a projection formed on each widened end portion and adapted to be engaged beneath the shank of the shoe.

2. A device of the character described adapted to be connected to a shoe or removed therefrom as a unitary device consisting of a strip of readily flexible material adapted to be shaped around the shoe upper, teeth formed on one edge of the strip, said toothed edge being bent to provide a continuous flange to be engaged between the sole and upper, and a projection on each end of the strip adapted to be engaged beneath the shank of the shoe.

3. A device of the character described adapted to be used in the repairing of shoes consisting of a strip of readily flexible material adapted to be shaped around the shoe upper and bent to provide a flange to engage between the upper and sole and end portions to be engaged beneath the shank of the shoe.

In testimony whereof I hereunto affix my signature.

DOMENIC CALO.
